CLAIM

The ornamental design for an element of a shoe upper, as shown and described.

DESCRIPTION

FIG. 1 is a left side elevational view of an element of a shoe upper showing our new design;

FIG. 2 is a right side elevational view thereof; and

FIG. 3 is a rear elevational view thereof.

The broken line showing of a shoe in FIGS. 1-3 is environmental only and does not form part of the claimed design.

FIG. 1

FIG. 2

FIG. 3
